E. B. STIMPSON.
BATHING SHOE.
APPLICATION FILED NOV. 1, 1920.

Patented Oct. 24, 1922.

UNITED STATES PATENT OFFICE.

EDWIN B. STIMPSON, OF BROOKLYN, NEW YORK.

BATHING SHOE.

Application filed November 1, 1920. Serial No. 420,927.

To all whom it may concern:

Be it known that I, EDWIN B. STIMPSON, a citizen of the United States, residing at Brooklyn, in the county of Kings and State 5 of New York, have invented certain new and useful Improvements in Bathing Shoes, of which the following is a specification.

This invention relates to bathing shoes and aims to provide a construction which 10 will prevent the accumulation of sand in the shoe when it is being worn.

It is a common experience that with the ordinary bathing shoe sand finds its way into the interior, usually from the top, and 15 lodges in the bottom of the shoe and causes discomfort to the toes and sole of the foot. Accordingly, I propose to provide the shoe with holes or perforations or apertures located at low points of the shoe, in such a 20 way and of such size that sand which may find its way into the interior of the shoe, may readily pass out through these openings; in other words, recognizing that it is perhaps impractical to prevent the entrance 25 of sand into the shoe, I provide for its escape, and against the possibility of substantial accumulation. I prefer that these sand outlets shall be located, for the most 30 part, in the sole of the shoe, though some may also be provided within the upper immediately adjacent the sole.

A further object of the invention is to define the apertures or sand outlets by means 35 of metallic eyelets or the like which will serve the additional function of reinforcing the sole or other member which carries them, and which, in the case of a shoe that is provided with a lining, will prevent objectionable 40 creasing or bunching of the lining and keep it in a desirably smooth condition.

Other objects and aims of the invention, more or less broad than those stated above, together with the advantages inherent, will be in part obvious and in part specifically 45 referred to in the course of the following description of the elements, combinations, arrangements of parts, and applications of principles constituting the invention; and the scope of protection contemplated will 50 appear from the claim.

In the accompanying drawings, which are to be taken as part of this specification, and in which I have shown merely a preferred 55 form of embodiment of invention,

Figure 1 is an elevation of a bathing shoe embodying my invention;

Figure 2 is a bottom plan view of the same;

Figure 3 is a section taken on the line 3—3 of Figure 1; 60

Figure 4 is a partial bottom plan view similar to Figure 1, showing the sand-escape openings in the form of slits cut through the sole; and

Figure 5 is a view similar to Figure 3 65 illustrating a shoe provided with the sort of sole shown in Figure 4, and without a lining, and with additional escape openings in the piece which joins the sole and the upper. 70

Referring to the numerals on the drawings, there is shown at 6 a bathing shoe of usual construction, having a sole 7. In Figures 1, 2 and 3 the sole 7 (including also the flat heel portion), is provided with a 75 considerable number of openings, each of which is defined by a metallic eyelet 8, the shank of which passes through the sole and also through the lining 9. The number of the apertures defined by the eyelets, and 80 their size, will be empirically determined with the idea of attaining the stated objects of the invention without interfering too much with flexibility and comfort. Any sand which finds its way into the shoe from 85 the top, or which would tend to enter by way of the eyelets, will be washed out just as soon as the wearer enters the water, because obviously there will be a circulation due to gravity from the top to the bottom 90 of the shoe, and the sand and water-escape openings are at the low point, that is, in the sole.

As shown in Figure 4, the openings may be cut directly in the sole, a number of slits 95 10 being shown in that figure and also in Figure 5. If these slits were to be made in a lined shoe however, the lining would also be slotted; and since the lining is usually a very flimsy material it might tend to crease 100 and bunch and therefore give discomfort to the wearer. Accordingly, I prefer that the slotted openings 10 shall be used with such a shoe as is shown in Figure 5, where there is no lining, and in which the piece 11 which 105 joins the sole 7 to the upper 12, is connected to these parts by means of outwardly turned seams. It will be understood that the reason for having the lining 9, as in Figure 2, is that bathing shoes are usually made with a 110 connecting piece 11 whose junction with the sole is by means of an inwardly turned seam,

which would cause discomfort if it were not covered by the lining 9. Accordingly, I propose to do away with the inwardly turned seams and thereby eliminate the necessity for 5 a lining, so that I can provide the sand-outlet slits 10 in the sole with good results so far as the attainment of the principal object of this invention is concerned.

As suggested above, in all cases the size, 10 tread, and disposition of the sand-outlet openings will be empirically determined, having in mind the objects sought and the general construction of the shoe and the comfort of the wearer.

15 If desired or found advantageous, sand-escape openings may be employed in other places besides the sole, for instance, in the connecting piece 11, as shown in Figure 5. It is of importance, however, that sand-escape openings shall be provided which extend through the tread portions of the shoe, 20 though additional escape openings may be provided in portions other than the tread portions.

25 Inasmuch as many changes could be made

in the above construction, and many apparently widely different embodiments of my invention could be made without departing from the scope thereof, it is intended that all matter contained in the above description or 30 shown in the accompanying drawings shall be interpreted as illustrative and not in a limiting sense.

It is also to be understood that the language used in the following claim is intended to cover all the generic and specific features of the invention herein described and all statements of the scope of the invention, which as a matter of language, might be said to fall therebetween. 35 40

I claim:—

A bathing shoe having a solid sole provided with a multiplicity of apertures extending through its tread portion, the apertures being of such size and arrangement as 45 to permit the escape of sand from the interior of the shoe.

In testimony whereof I affix my signature.

EDWIN B. STIMPSON.
